UNITED STATES PATENT OFFICE.

WILLIAM G. LATIMER, OF DETROIT, MICHIGAN, ASSIGNOR TO THE LATIMER CASH REGISTER COMPANY, OF SAME PLACE.

CASH REGISTER AND INDICATOR.

SPECIFICATION forming part of Letters Patent No. 430,391, dated June 17, 1890.

Application filed January 27, 1890. Serial No. 338,298. (No model.)

To all whom it may concern:

Be it known that I, WILLIAM G. LATIMER, a citizen of the United States, residing at Detroit, in the county of Wayne and State of

Michigan, have invented certain new and useful Improvements in a Cash Register and Indicator, of which the following is a specification, reference being had therein to the accompanying drawings.

10 This invention relates to new and useful improvements in a cash register and indicator; and the invention consists in the peculiar construction of a device for locking the tablet-holding rods and the register-actuating rods; 15 and, further, in the peculiar construction of an apparatus designed to prevent the simultaneous operation of two or more keys; and, further, in the peculiar construction, arrangement, and combination of the parts, all as 20 more fully hereinafter described.

In the drawings, Figure 1 is a vertical section through my machine. Figs. 2 and 3 are similar sections showing the tablet-rods, registering-rods, and connecting mechanism at 25 different points of operation. Fig. 4 is a cross-section on line $x-x$ in Fig. 1. Fig. 5 is a similar section showing one of the keys operated. Fig. 6 is a similar section showing a modification.

30 The invention herein described is designed to be an improvement upon my previous patent, No. 409,107, dated August 13, 1889, and upon my application for patent, Serial No. 326,805.

35 A is a case of the machine in which are the series of keys B, pivoted to the transverse shaft C, and each key supporting at its rear end a tablet-rod D and a registering-rod E.

F is the registering mechanism, designed to 40 be operated through the medium of the swinging rack-bar F', which is secured to the upper end of the registering-rods and is adapted to engage into the gear-toothed roller G, through which motion is transmitted to the 45 registering mechanism. Each of the tablet-rods carries an indicating-tablet G'.

Suitable guides H and I are arranged for the tablets and registering-rods. The registering-rods are preferably connected to the 50 keys pivotally by means of the stirrups—such as I'—these parts being the same as

shown in my previous patent and application for patent referred to, and operated as described and shown therein in a well-known manner.

55 The keys in my machine are preferably arranged in banks, representing, respectively, units, tens, and hundreds, and each bank of keys has its own registering mechanism and operates such registering mechanism.

I will first describe the operation of the device for preventing the simultaneous operation of two or more keys, the same consisting of a flexible chain or cord J fixably secured at its ends to the side of the machine. In 60 this machine the keys are arranged in groups, and in such a machine each group has a separate cord J secured at the side of the group upon suitable cross-bars J'. d d' are a series of guides arranged below the keys (or if in 65 the rear of the shaft C above the keys) and forming between them guide grooves or spaces for the keys. The cord J, secured at its ends to the cross-bars J', lies loosely upon the tops of the guides d d', having slack enough to allow of the depression of one key only, the slack being taken up in the loop e, formed under the key between the guides. The cord is stretched tightly over all of the remaining 70 guide-grooves, this preventing the depression 75 of the keys therein, as shown in Fig. 5. While I preferably use this construction it may be varied to the form shown in Fig. 6, wherein the cord is formed into the loops a, which pass under each key at its lower end and into 80 the loops b between each of the keys which pass over the rods or bearing c. The length of the cord is such that it will allow of the depression to the full extent of one of the keys; but when one key is thus depressed 85 there is no slack in the cord to allow of the depression of any of the other keys, as shown in Fig. 5. As soon as the key—such as B—is released it assumes its upper position, as shown in dotted lines in Fig. 5. It is evident upon the depression of any key that the slack will be taken up by such key in its depression, the flexible cord simply pulling over the bearing c and under the keys. It will thus be seen that no two keys of any bank can be 90 operated simultaneously to their full extent. The object of this is to prevent the simulta-

neous operation of two keys, whereby but one might register, and a dishonest employé might put two small amount in the cash-drawer to offset any such registration.

5 The next feature of my improvement relates to the means for holding up the tablet-
rods, and the same consists in journaling in
the rear of the tablet-rods a cam-eccentric or
a bar acting as a wedge.

10 In the drawings I have shown a universal
bar L pivoted in the sides of the frame held
from downward movement by a stop—such
as L'—but free to move upwardly. This bar
enters a cut-away portion or notch M in the
15 rear side of each tablet-rod. O is a shoulder
arranged some distance below the notch on
the rear side of each tablet-rod and in such
relation to the length of the tablet-rod that
it will strike the bearing L just before the
20 tablet-rod has been raised to its highest point,
for the purpose as more fully hereinafter de-
scribed.

The operation of these devices is as fol-
lows: When a key is depressed it carries with
25 it, in the upward movement of the rear end,
its tablet-rod. As soon as the tablet-rod be-
gins its upward movement the shoulder a',
below the cut-away portion M in the tablet-
rod, strikes the under side of the bar L and
30 swings it upward to the position shown in
Figs. 2 and 3, allowing the tablet-rod to come
up; but in case the operator releases his hold
of the key the tablet-rod would be held in its
elevated position by the wedging action of
35 the friction-bar L against the rear side of the
tablet-rod, as shown in Fig. 2. Just before the
key has completed its movement the shoulder
O will strike the under side of the bar and
raise it clear therefrom, as shown in Fig. 3,
40 thus allowing any key which may have been
previously elevated to fall; but as soon as
the operator releases his hold of the key the
friction-bar L will again come in contact with
the rear side of the tablet-rod and hold it in
45 its elevated position, so that the tablet may
be seen from the front of the machine in the
usual manner. It will be seen that as the
cut-away portion M of the unoperated tablet-
rods is opposite the friction-bar L, and as that
50 portion of the operated tablet-rods upon
which the friction-bar engages extends across
that cut-away portion, only the operated tab-
let-rods will receive the friction of the bar,
thereby making it more efficient than if the
55 friction-bar touched all of the keys.

While I show in this application a bar act-
ing as a wedge it is evident that a cam or an
eccentric would effect the same result.

The registering-rods I desire to lock in their
60 elevated position at any point of partial reg-
istration, but allow them to fall as soon as
the registration is completed. To this end I
have arranged the friction-bar Q, pivotally
supported at the sides of the machine, or in
65 suitable cross-bars upon the side of each bank
of keys, and this bar is held normally in hori-
zontal position by means of a spring Q', slid-

ing between two guides Q². Any other form
of spring may be used, as may be desired. I
simply show this as being a simple form of
70 construction. The forward edge of this fric-
tion-bar Q engages into corresponding cut-
away portions or notches R in the front side
of all of the registering-rods.

S is another cut-away portion or notch in
75 each of the registering-rods at the point which
will be opposite the friction-bar when the rods
are in their highest position.

The operation of this device is as follows:
As soon as the operator has depressed the key
80 the shoulder b' at the lower edge of the notch
R strikes the under side of the friction-bar
and causes it to assume the inclined position,
as shown in Fig. 2, bearing with its inner
edge against the rear side of the registering-
85 rod. It is evident that the registering-rod
can freely pass upward with the bar in this
position; but if at any point of partial reg-
istration the operator should release his hold of
the key the rod could not fall because of the
90 frictional contact of the bar with the reg-
istering-rod thus elevated. As soon as the reg-
istration is completed the bar R is brought
opposite the lower notch S in the registering-
95 rod, which it enters, assuming its horizontal
position, as shown in Fig. 3. As soon as the
operator releases his hold of the key it is evi-
dent that the registering-rod can freely de-
scend. The shoulder c' at the upper edge of
100 the notch S will strike the friction-bar and
incline it downwardly until it reaches the
notches R, when it will again assume its hori-
zontal position. A cam or an eccentric will
act in the same manner as this friction-bar,
105 which has simply a wedging action, wedging
the registering-rod between the friction-bar
and the guides. It is evident that in this con-
struction, as in that of the tablet-rods pre-
viously described, as the friction-bar Q is op-
posite the cut-away portion R, common to all
110 the rods, and as the bearing-portion T be-
tween the cut-away portions in the operated
rod extends across the cut-away portion R
in the unoperated rods, the friction will be
brought to bear only upon the operated rod,
115 thus making it positive in its action, as the
key is locked to the registering-rod by means
of the stirrup I'. The key itself is locked in
120 its depressed position, should the operator re-
lease it at any point of an uncompleted reg-
istration. It is evident that the tablet-rod or
the registering-rod is clamped in its elevated
position between its guide and the friction-
bar, and that such clamping is due entirely to
the eccentric arrangement of the friction-bar
125 in relation to the rod and the weight of the
rod—in other words, that the tablet-rod is held
up by the clamping effect due to its weight
acting between an eccentric or wedging-bar
and the guides.

What I claim as my invention is—

1. In a cash register and indicator, the com-
bination, with a series of keys and series of
tablet-rods operating thereby in guides, of a

horizontal friction-bar pivoted at its outer edge, bearing against said tablet-rods in their elevated position, and held in binding-contact with the vertical edge thereof by the weight 5 of the rod, substantially as described.

2. In a cash register and indicator, the combination, with a series of keys and a series of tablet-rods operated thereby, moving in guides, of a corresponding notch or cut-away 10 portion in each of said rods, a friction-bar pivotally secured opposite said notch, extended therein and adapted to bear against said tablet-rods in their elevated position and clamp them between said bar and the guides, 15 substantially as described.

3. In a cash register and indicator, the combination, with a series of keys and a series of tablet-rods operated thereby, of guides in which the said tablet-rods move, a horizontally-disposed friction-bar pivotally secured 20 at its outer edge in rear of said rods in binding contact with the vertical edge of the rods, whereby the rods are held against the guides, and tripping mechanism, substantially as described, for releasing such frictional contact 25 upon the operation of a key, substantially as described.

4. In a cash register and indicator, the combination, with a series of keys and a series of 30 tablet-rods operated thereby, of guides in which said tablet-rods move, a horizontal friction-bar pivotally secured at its outer edge in the rear of said tablet-rods, normally held in binding contact therewith during its upward movement and adapted to wedge said 35 rods against the said guides by the weight of the rods, and a shoulder at or near the lower end of said tablet-rods to trip said friction-bar upon the operation of a key, substantially as 40 described.

5. In a cash-register, the combination, with a series of keys, of a series of notched tablet-rods operated by the keys, a pivoted friction-bar normally held in a horizontal plane with the pivots resting in said notches and arranged to bear against the rods in their elevated position, and a shoulder on the rods for tripping the bar, substantially as described. 45

6. In a cash-register, the combination, with a series of keys and a series of registering- 50 rods operated thereby moving in guides, of a series of corresponding notches on said rods, and a friction-bar engaging into said notches and adapted to clamp the registering-rod against the guide at any point of partial registration, substantially as described. 55

7. In a cash-register, the combination, with a series of keys and a series of registering-rods operated thereby moving in guides, of two series of corresponding notches in said 60 rods, and a friction-bar engaging into the upper series of notches, adapted to wedge an operated registering-rod against the guides at any point between the two notches and to be released therefrom upon entering the lower 65 notch, substantially as described.

8. In a cash register and indicator, the combination of a series of keys and a series of tablet-rods operated thereby, of a gravity-latch engaging only the operated tablet-rods 70 to hold them in their elevated position at any point during partial registration, substantially as described.

In testimony whereof I affix my signature, in presence of two witnesses, this 16th day of December, 1889. 75

WILLIAM G. LATIMER.
